UNITED STATES PATENT OFFICE.

FRANK KUHN AND FRANK E. SHAILOR, OF DETROIT, MICHIGAN, ASSIGNEES TO
AMERICAN ELECTRICAL HEATER COMPANY, OF DETROIT, MICHIGAN, A COR-
PORATION OF MICHIGAN.

ELECTRICAL HEATING UNIT.

1,154,409.

Specification of Letters Patent. Patented Sept. 21, 1915.

Application filed October 16, 1909. Serial No. 523,016.

To all whom it may concern:

Be it known that we, FRANK KUHN and FRANK E. SHAILOR, citizens of the United States of America, residing at Detroit, in the county of Wayne and State of Michigan, have invented certain new and useful Improvements in Electrical Heating Units, of which the following is a specification, reference being had therein to the accompanying drawings.

The invention relates to electrical heating units designed for use in various constructions of electrical heaters, and it is the object of the invention to obtain a thoroughly protected or armored heat generating resistance, and one in which the heat is dissipated through conductor from all portions of the resistance.

To this end, the invention consists in the construction as hereinafter set forth.

In the drawings—Figure 1 is a perspective view of one form of unit; Fig. 2 is a perspective view with a portion of the armor and an insulating plate broken away, of a slightly modified construction, the resistance element being diagrammatically shown; Fig. 3 is a conventional section on line $x-x$, Fig. 1.

The heating resistance is preferably formed of a flattened metallic strip, which extends in a zig-zag course, having a surface of the desired area, the resistance being represented diagrammatically at A in Fig. 1. Upon opposite sides of this strip are placed insulating plates B, preferably of mica, and over this is arranged a metallic sheathing or armor composed of plates C and D secured to each other at their margin by overlapping flanges E. To hold these plates in firm contact with the mica and resistance throughout their extent, a plurality of intermediate stays F are employed and these as shown, are in the form of hollow rivets which pass through the insulating plates and armor plates but avoid the resistance.

G are terminals which in the construction shown in Fig. 1, are mechanically secured to metal plates H attached to the ends of the plates C and D by rivets J. The ends I of the resistance are clamped between the

flange K on the terminal, and a washer L, the several parts of the terminal being suitably insulated from the plate H.

In Fig. 2 the support for the terminal is formed by an integral extension of the plates C and D but the resistance is connected to the terminal in the same manner as described in connection with Fig. 1.

In use the construction of the unit described will be thoroughly protected from injury and from short circuit, and at the same time the heat is dispersed with almost as great facility as from the base resistance.

What we claim as our invention is:

1. A flat heating unit, comprising a flat resistance element, flat insulation upon opposite sides of the resistance, a flat armor inclosing the resistance and insulation and firmly clamping the insulation and resistance therebetween, and plug engaging terminals carried by and insulated from said armor and forming with the latter, the resistance and the insulation a unitary structure.

2. A flat heating unit, comprising a flat resistance element, flat insulation upon opposite sides of the resistance, a flat armor inclosing the resistance and the insulation and firmly clamping the resistance and insulation therebetween, said armor having a projection, and plug engaging terminals rigidly carried by said projection and insulated therefrom, said resistance, armor and terminals forming a unitary structure.

3. A flat heating unit, comprising a flat resistance element, flat insulator plates upon opposite sides of said resistance, armor plates parallel to the insulator plates positioned upon opposite sides of the latter and united to each other at the margins thereof, a plurality of spaced hollow rivets passing through said insulator plates and armor plates to prevent buckling thereof, and plug engaging terminals carried by said armor plates and forming a unitary part of the heating unit.

4. A flat heating unit, comprising a flat resistance element, flat insulator plates upon opposite sides of said resistance, armor plates parallel to the insulator plates positioned upon opposite sides of the latter and

united to each other at the margins thereof, and rigid plug engaging terminals carried by said armor plates and forming a unitary part of the heating unit, and an intermediate stay for clamping the armor against the inner structure, said stay passing through the insulator plates and avoiding the resistance.

In testimony whereof we affix our signatures in presence of two witnesses.

FRANK KUHN.
FRANK E. SHAILOR.
